LADY'S HANDBAG

Rudolph Lobel, New York, N. Y.

Application June 5, 1940, Serial No. 338,877

1. Claim. (Cl. 150—28)

This invention relates to ladies' handbags and methods of making the same.

One object of the invention is to provide an improved lady's handbag which is very simple and inexpensive to manufacture, and which is capable of producing a handbag of fine appearance while affording a great range of styling possibilities.

Another object is the provision of an improved method for effecting the above in a frame-bag, without requiring the usual stuffing and clamping of fabric in channel frames.

The almost universal method used in making ladies' frame handbags is by first stuffing the material into the channels of the frame members and then clamping the same on the goods. In producing styling and ornamental effects as by pleating or gathering the material, considerable skill and care is necessary to distribute the material in the channels just right. In fixing one spot the gather is upset at another; sometimes the fabric slips out at certain points. This work requires a highly skilled mechanic, and in handbags of quality, is a principal item in the cost of production. Finally, the handbag must be carefully manipulated to clamp the channel frames without disturbing the goods, and a special machine is required, carefully operated, in order not to mar or scratch the frame members, because then the handbag would be defective.

It is therefore an object of the invention to overcome these drawbacks and difficulties and to produce a high grade lady's handbag.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a view in side elevation showing a lady's handbag embodying the invention.

Fig. 2 is a view in end elevation thereof.

Fig. 3 is an inside view in elevation of one-half thereof, with the other half cut away.

Fig. 4 is an enlarged fragmentary sectional view of the handbag showing the connecting means.

Fig. 5 is an edge view of a decorative fastener.

Figs. 6 and 7 are enlarged sectional views of modified fastener means.

Fig. 8 is a side view on a reduced scale of a bag body before attachment to the frame.

The advantages of the invention as here outlined are best realized when all of its features and instrumentalities are combined in one and the same structure, but, useful devices may be produced embodying less than the whole.

10 It will be obvious to those skilled in the art to which the invention appertains, that the same may be incorporated in several different constructions. The accompanying drawing, therefore, is submitted merely as showing the preferred exemplification of the invention.

15 Referring in detail to the drawing, 10 denotes a lady's handbag embodying the invention. The same may comprise a bag body 11 having side walls 12 interconnected by end gussets 13. In horizontal section each of the latter has a pair of inward folds as at 14 and an intermediate outward fold 15 at which the purse 16 is suitably secured. When the bag body is opened, the gussets are stretched and the folds 14 disappear.

20 When the bag body is closed, the purse keeps the gussets spaced and stiffens them against distortion or collapse. The bag body is also provided with a lining throughout, the outer fabric showing the contrasting effect as in Fig. 3, at the top of the handbag.

25 Co-operating with the bag body 12 along the mouth thereof is a frame which may comprise a pair of inverted, U-shaped frame members 17 that are hingedly interconnected at their lower ends at 18. These frame members may consist of wood or other stiff or composition material into which a pin, such as a nail or screw may be driven. Such frame members may be covered with a textile fabric 18 as shown in Fig. 4. Also

30 the frame members may be pressed or cut out of plastic material, and the like. These frame members may be of any desired cross section, and, of course need not be of channel form. It will be noted that the side walls of the bag body

35 lie in substantially parallel planes and are formed with top or marginal portions 19 which project upward above the frame members 17. Hence the top sections of the frame members are substantially concealed by the projecting portions 19, since the frame members lie wholly inside of and between the planes of the side walls of the bag body. In consequence the upper edges 20 of the gussets slope downward rather sharply to pass under the top sections of the frame members and between the arms thereof. The latter

desirably may be partly concealed within the gussets.

The structure for securing the side walls to the frame will now be described. As seen in Fig. 4, the side wall 12 of the bag body may be affixed to a frame member by a nail or screw 22 piercing the side wall and driven into the frame member. The screw may have a coarse thread so as to be operative by pressure alone. In general, it may be referred to as a pin. Overlying and concealing the head of the pin is an ornamental member 23 which may be partly hollow and may have a pair of prongs 24 that are to be driven into the frame member through the side wall. The elements 22 and 23 may be considered as cooperative with each other to afford a fastening means.

As shown in Fig. 6, if a frame member 25 of molded material be used, it may have any suitable fasteners or sockets 26 molded therein or cemented into recesses thereof. Now a headed pin 27 may be forced through the pleat or side wall 28 of the handbag, with the pin shank suitably gripped or distorted in the socket for a tight securing.

In Fig. 7, a fastener element may comprise a pin or screw shank 29 fixed into frame member 30, and having a stop or pressure collar 31 from which extends a sharp pin 32. The pleat or side wall 33 of the bag body may be forced on the pin 32, and then an ornamental head 34 may be driven onto said pin 32 to reliably secure the bag body to the frame, as by flattening the point of the pin or by frictionally gripping the pin.

Various fastening means may be used for securing of the bag body and which permit the securing to be effected as the bag body is decoratively laid along the frame. Thus the bag body 35 from which the bag body 11 is formed, may be complete in all respects with outer fabric, lining, gussets and purse mounted thereon, but the part at the top or mouth 36 being substantially longer than that at the bottom of the bag body. The mouth may be scalloped or otherwise constructed with a decorative configuration as shown. When secured to the frame, the bag body 35 assumes the shape shown at 12, being pleated in an upright direction, as indicated by the pleats 37, arranged according to a predetermined design. The fastening means

22, 23 secure the pleats to the frame to fix the same and to support the bag body on the frame. This pleating produces a desired decorative effect of the edge 36. Moreover, the pleats stiffen the portion 19 of the bag body which projects above the frame, free thereof.

According to my method, the bag body 35 is laid along the frame and the pleats then formed, and secured to the frame by the fastening means. 10 In other words, the pleats may be open and unsecured except for said fastening means. With a structure such as shown in Fig. 7, the advantages are particularly clear. The fasteners are placed in predetermined positions and serve 15 as indicators for locating the pleats and the distribution of the material. The operator manipulates the fabric and presses it onto the gage pins 32 and applies the sockets 34, completing the handbag.

20 It will thus be seen that I have provided a handbag and method of making the same which fulfill the objects of the invention and are well adapted for practical use.

I claim:

25 A lady's handbag including a bag body having a mouth defined by end walls and side walls, the material of the latter being substantially greater in length at the mouth than at the bottom but with the side walls having pleats increasing in width toward the mouth to thus reduce the overall length of the material of the side walls at the mouth, a frame for said mouth comprising frame members movable toward and away from each other, the side walls of the bag body lying 30 wholly at the outer sides of the frame members, and clamping fasteners extending through the pleats, constructed and arranged for permanently securing the pleats to the frame members to thus reenforcingly mount the bag body and 35 to clamp the pleats in relatively thin form and to thus maintain the pleats in position on the frame members, the side walls being otherwise substantially free of the frame members, and the pleats being otherwise substantially free and 40 open, whereby the tension on the bag body in carrying articles is transmitted to the frame members only through the pleats to cause the pleats to be maintained smooth and taut and to prevent distortion of unsecured portions of 45 the bag body intermediate of the pleats.

50 RUDOLPH LOBEL.
